DESIGN FOR A LAPEL BUTTON

Gustave W. Carlson, Superior, Wis.

Application January 6, 1940, Serial No. 89,337

Term of patent 3½ years

To all whom it may concern:

Be it known that I, Gustave W. Carlson, a citizen of the United States, residing at Superior, in the county of Douglas and State of Wisconsin, have invented a new, original, and ornamental Design for a Lapel Button, of which the following is a specification, reference being had to the accompanying drawing, forming part thereof.

In the drawing:

Figure 1 is a top plan view of a lapel button, showing my new design.

Figure 2 is a side elevation, looking at the head of the screw.

Figure 3 is a side elevation at right angles to Figure 2.

Figure 4 is a side elevation looking at the point of the screw.

I claim:

The ornamental design for a lapel button, as shown.

GUSTAVE W. CARLSON.
